UNITED STATES PATENT OFFICE.

RICHARD DIMES, JR., OF WINTHROP, MASSACHUSETTS, ASSIGNOR TO RICHARD DIMES CO., OF BOSTON, MASSACHUSETTS, A CORPORATION OF MASSACHUSETTS.

DESIGN FOR A DISH OR ANALOGOUS ARTICLE.

Application filed December 31, 1928. Serial No. 29,462. Term of patent 7 years.

To all whom it may concern:

Be it known that I, RICHARD DIMES, Jr., a citizen of the United States, residing at Winthrop, in the county of Suffolk and State of Massachusetts, have invented a new, original, and ornamental Design for Dishes or Analogous Articles, of which the following is a specification, reference being had to the accompanying drawing, forming part thereof in which—

Fig. 1 is a plan view of a dish showing my new design and

Fig. 2 is a view thereof in side elevation.

I claim:

The ornamental design for a dish or analogous article, as shown.

In testimony whereof, I have signed my name to this specification.

RICHARD DIMES, JR.
